CONTROLLING DEVICE.

1,380,486.

Specification of Letters Patent. Patented June 7, 1921.

Application filed April 18, 1919. Serial No. 291,009.

To all whom it may concern:

Be it known that I, SAM G. Langley, a citizen of the United States, and a resident of Maplewood, in the county of Essex and 5 State of New Jersey, have invented certain new and useful Improvements in Controlling Devices, of which the following is a description.

This invention relates to controlling devices of general application but especially 10 adapted for starting and stopping the movement of the record support or mandrel forming a part of business phonographs. In carrying out the invention electro-magnetic 15 devices are utilized.

An object of the invention is to provide a construction in which the objectionable heating and sparking thereof is avoided, in which the movement is positive in both 20 directions and in which the control can be held positively in either position.

Another object of the invention is to provide a construction which is compact, in which the coils are but momentarily energized and can be used on either alternating 25 or direct-current and which is practically noiseless.

The above results are attained by means 30 of a construction wherein, when the circuit of the electro-magnetic devices is closed to start or stop the record support, it is allowed to remain closed just long enough to produce the desired effect. It is then automatically and quickly broken whereby the flow of current is arrested and prolonged heating or 35 continued sparking of the apparatus is prevented. The preferred construction is such that when the controlling mechanism is operated to start the movement of the record support, further operation of said mechanism 40 cannot affect the movement of the record support except to stop the same and vice versa. The controlling mechanism is accordingly very certain and efficient in operation.

Other objects of the invention will appear more fully in the following specification and appended claims.

Referring to the drawing in which the 50 same reference characters are used to indicate the same parts throughout the several views,

Figure 1 is a front view with parts broken away showing the application of the pre-

ferred form of my invention to a phonograph.

Fig. 2 is a rear view of the electro-magnetic device.

Fig. 3 is a view thereof looking at one side, 60

Fig. 4 is a view thereof looking at the opposite side, the device being shown in Figs. 2, 3 and 4 in inverted position and with the armatures in position to actuate the mandrel.

To illustrate the application of the invention, a well known type of controlling mechanism for phonographs used for business purposes is first described. Referring to the drawing, the character A designates a cylindrical sound record or blank carried by a 65 rotatable mandrel or support 1. The support 1 is mounted upon a cabinet 2 and is arranged to be rotated by a shaft comprising sections 3 and 3^a carried in bearings formed in standards 4 and 4^a respectively upon the 70 cabinet 2. On the section 3^a of the shaft is splined a clutch collar 5, this clutch collar being free to slide along the section 3^a of the shaft but forced to rotate with it. A driven pulley 6 which is made fast to the 75 shaft section 3 carries a hub forming a clutch member 7 arranged to coöperate with the collar 5. A belt 8 connects the pulley 6 with a suitable source of power, not shown. The clutch collar 5 is moved into and out of 80 engagement with the clutch member 7 by means of a member 9 which is preferably mounted in an upright position on the top of the cabinet 2 and has its upper end bent away from the observer viewing the apparatus from the position shown in Fig. 1 and 85 is provided with projections 10 engaging a circumferential groove 11 in the collar 5. 90

At its lower end below the top of the cabinet 2, the member 9 is provided with an 95 arm 12 which, viewing the apparatus as shown in Fig. 1, extends toward the observer, and to the forward end of this arm is pivoted one end of a link 13 which is pivoted at its other end to an armature of the electro-magnetic device as hereinafter more fully 100 described.

The electro-magnetic device for actuating the clutch collar 5 comprises a supporting plate 14 secured below the top of the cabinet 2 and to which are secured two pairs of 105 electro-magnets having coils 15 and 16 arranged in parallel relation and vertically.

- The coils 15 and 16 are provided with U-shaped armatures 17 and 18 pivoted at their free ends to the plate 14 upon parallel axes 19 and 20 each extending transversely of the 5 coils and intersecting the axes of its pair of coils. Each armature extends along the sides of its pair of coils and over the free ends thereof, the active or intermediate part of each armature being mounted to move in 10 a direction transversely of the free ends of its pair of coils when attracted. The above described link 13 is connected to one of these armatures and as here illustrated the armature 17.
- 15 At one side of the coils and armatures is a vertically arranged plate 21 attached to the supporting plate 14 and composed of insulating material. A vertically arranged arm 22 mounted independently of and interposed 20 between the U-shaped armatures and adapted to be actuated thereby is pivoted at its end adjacent to the plate 14 to the plate 21 on an axis parallel with the axes 19 and 20, being provided with a pivot pin 23 projecting 25 through to the opposite side of the plate 21. The arm 22 is provided with suitable shock and noise-absorbing material 24, preferably felt, against which the armatures strike when actuated.
- 30 The plate 21 at one side is provided with spaced portions 25 and 26 to which are secured spaced contacts 27 and 28 having main portions 29 arranged in a plane substantially parallel with the plane of the plate 35 21 and having their adjacent edges 30 bent at an angle to the plane of the main portions, into the space 31 between the portions 25 and 26. Secured at one end to the projecting end of the pivot pin 23 is a movable 40 switch contact 32 having its opposite end 33 engageable with the spaced contacts 27 and 28 and adapted to slide or brush thereover whereby the circuits through the coils are controlled. The lateral edges 34 of the 45 engaging portion or end 33 of the switch contact 32 are bent outwardly from the main portion thereof in a direction the reverse of the adjacent edges 30 of the spaced contacts 27 and 28. This construction prevents 50 sparking and corrosion as the switch contact 32 moves back and forth from one fixed contact to the other.
- In order to provide a combined snap for the switch and means to prevent the actuation of either armature until the other reaches attracted position, which in the construction here illustrated is slightly inwardly 55 from the vertical as shown in Fig. 3, and to insure the actuation of the remaining armature to open the circuit of the energized coils when the attracted armature reaches its attracted position at the completion of its movement, a spring 35 is provided which is tensioned by the movement of either armature to attracted position and, as here illus-

trated, connects the two armatures and cooperates with inwardly extending members 36 and 37 upon the armatures engaging each other and adapted to prevent the actuation of one armature under the tension of its 70 spring until the other armature reaches attracted position. Each member 36 and 37 has a curved edge 38 concentric with the pivot of its armature and adapted to be engaged by a curved end 39 of the member of 75 the other armature. It is seen that when one armature is moving to attracted position its concentric edge supports and holds the other armature, and releases it only when the movement is completed, the members 80 then engaging in the reverse order so that when the other armature is attracted the first armature is supported and held until the completion of the movement of the latter armature. A vertically arranged strip 40 85 of felt is arranged in the path of movement of armature 18 to absorb shock and noises when the armature moves to attracted position.

The electrical connections for the electro- 90 magnetic device are shown diagrammatically in Fig. 1. As there illustrated the contact 27 is in circuit with the coils 15 through a conductor 41, the coils 15 being arranged in series and connected by the conductor 42. 95 A conductor 43 terminating in a fixed contact 44 leads from the coils 15. The fixed contact 28 is in circuit with the coils 16 through a conductor 45, coils 16 being in series with each other through conductor 46. 100 A conductor 47 leads from the coils 16 and terminates in a fixed contact 48 in spaced relation to the contact 44. The switch contact 32 is in circuit with one part 49 of the main line and a switch 50 in circuit with the 105 other part 51 of the main line is interposed between the fixed contacts 44 and 48 and is adapted to alternately engage the same as desired.

The operation of the form of my invention disclosed is as follows:

When it is desired to start the mandrel, the parts being in the position shown in Fig. 1, the switch 50 is moved into engagement with the contact 44, closing the circuit 115 through the coils 15 energizing the same and causing the armature 17 to move from the position shown in Fig. 1 to the position shown in Fig. 3, thereby actuating the link to cause the engagement of the clutch members and start the mandrel. When the clutch members are engaged, the armature 17 will assume substantially the position shown in Fig. 3. During the movement of the armature 17 the curved end 39 of the 120 armature 18 is in engagement with the curved edge 38 of the armature 17 and thus held against movement, the position of the two parts being the reverse of that shown in Fig. 3. Of course the movement of the 130

armature 17 to attracted position, tensions the spring 35 so that when this armature reaches the attracted position, the armature 18 is released and thrown to the position shown in Fig. 3 against the arm 22, moving the same and swinging the switch contact 32 out of engagement with the contact 27 and into engagement with the contact 28 as shown in Fig. 4, thereby opening the circuit through coils 15 and placing coils 16 in position to be energized when switch 50 is actuated in the reverse direction. It will thus be seen that there is provided automatic means for opening the circuit through the coils at the completion of each movement of the device. When it is desired to stop the rotation of the mandrel the switch 50 is moved into engagement with the contact 48, thereby closing the circuit through the coils 16. The armature 18 is thereupon attracted and moved to a position corresponding to the position of the armature 17 shown in Fig. 3. During the movement of the armature 18 however it will be seen that the armature 17 is held stationary by reason of its engagement with the curved edge 38 of the armature 18 and that the spring is tensioned. When the armature 18 reaches the attracted position the armature 17 is released and the spring draws the same inwardly, throwing out the clutch and moving the intermediate arm 22 to the position shown in Fig. 1 and the switch contact 32 into engagement with the fixed contact 27, thereby automatically opening the circuit through the coils 16 and placing the coils 15 in position to be energized when the switch 50 is again actuated.

In providing U-shaped armatures pivoted substantially as shown and having transverse portions extending over the free ends of the coils, as the transverse portions approach the attracted position, the transverse resultant of the attractive force tending to move the armatures toward the coils decreases so that when the armature reaches substantially its vertical position the transverse resultant tending to move the armature to vertical position is practically zero, the attractive force being then entirely downwardly. This arrangement reduces the momentum of the armature considerably so that when it reaches its attracted position it is easily stopped, reducing noise and wear and tear.

By the above construction it will be seen that the clutch can be thrown in and out positively and that the armatures are actuated with very little noise. The automatic switch controlling the circuits through the coils is stationary until the completion of the movement of each armature and is then thrown with a snap by the spring to open one circuit and place the other in condition to be closed whereby the circuits through the pairs of coils must be closed alternately, the

switch being mounted independently of the armatures and controlled first by one armature and then the other.

It is to be understood that the invention is not limited to the embodiments and features specifically shown and described herein but that such embodiments and features are subject to changes and modifications without any departure from the spirit of the invention.

75

Having now described the invention, what is claimed as new and what it is desired to protect by Letters Patent of the United States is as follows:

1. In a device of the character described, a movable member, electro-magnets having independently mounted armatures for controlling said member and a switch comprising a movable contact mounted independently of said armatures and adapted to be controlled thereby to control the circuits of said electro-magnets, substantially as described.

2. In a device of the character described, a movable member, electro-magnets having independently pivoted armatures adapted to control said member, a movable arm between said armatures and controlled by the movement thereof and a switch for controlling the circuits through said electro-magnets and controlled by said arm, substantially as described.

3. In a device of the character described, a movable member, electro-magnets having armatures mounted for relative movement for controlling said member, an arm between said armatures provided with shock-absorbing material and controlled by the movement of said armatures and a switch controlled by said arm, substantially as described.

4. In a device of the character described, a movable member, electro-magnets having independently mounted armatures for controlling said member, a switch controlling the circuits of said electro-magnets and a snap device for throwing said switch when either armature moves to attracted position, substantially as described.

5. In a device of the character described, a movable member, electro-magnets having independently mounted armatures for controlling said member, a switch for controlling the circuits of said electro-magnets and controlled by said armatures and means for forcibly releasing either armature when the other reaches attracted position to actuate said switch, substantially as described.

6. In a device of the character described, a movable member, a plurality of electro-magnets for controlling said member and comprising coils and armatures pivoted on parallel axes and movable transversely of ends of said coils, means for actuating one armature when the other is attracted and

115

120

125

130

means for controlling the circuits of said coils, substantially as described.

7. In a device of the character described, a movable member, electro-magnets having pivoted armatures for controlling said member, means tending to actuate one armature when the other is attracted, holding means comprising a member on each armature having a curved edge concentric with the axis of its armature and a curved end coöperable with the concentric edge of the other member and adapted to release one armature when the other reaches attracted position and means controlled by said armatures for controlling the circuits of said electro-magnets, substantially as described.

8. In a device of the character described, a movable member, electro-magnets having armatures for controlling said member, holding members on said armatures coöperating with each other to maintain either armature stationary until the other reaches attracted position, a switch for controlling the circuits through said electro-magnets and spring means for actuating either armature and switch when the other armature reaches its attracted position, substantially as described.

9. In a device of the character described, a movable member, electro-magnets for controlling said member and having pivoted armatures with portions movable transversely of ends of said electro-magnets, means for holding one armature until the other is actuated, spring means connected to said armatures and tensioned by the movement thereof, an arm pivoted between said armatures and a switch secured to said arm and actuated when either armature is moved to attracted position and the remaining armature is released and moved by said spring means, substantially as described.

10. In a device of the character described, a movable member, a plurality of electro-magnets for controlling said member comprising coils arranged in parallel relation and U-shaped armatures, coöperating means on said armatures for maintaining one armature stationary until the other reaches its attracted position, a spring connecting said armatures, an arm pivoted at a point between said armatures and movable thereby, a switch controlled by said arm, and means for absorbing shock and noise upon the movement of said armatures, substantially as described.

11. In a device of the character described, a movable member, electro-magnets having armatures for controlling said member, means for holding one armature until the other is actuated, a switch for controlling the circuits through said electro-magnets, and means rendered effective to actuate

either armature and the switch when the other armature reaches its attracted position, substantially as described.

12. In a device of the character described, a movable member, electro-magnets having armatures for controlling said member, means for holding one armature until the other is actuated, means for controlling the circuits through the electro-magnets, and means rendered effective to actuate either armature and the circuit-controlling means when the other armature is actuated, substantially as described.

13. In a device of the character described, a movable member, a circuit-controlling switch, and electro-magnets having armatures for controlling said member and switch and provided with parts comprising coöperating means for holding one armature until the other is actuated, the movement of either armature to its attracted position effecting the release of said holding means and the actuation of the other armature and the switch, substantially as described.

14. In a controlling device, a pair of electro-magnets having armatures mounted independently of each other, a single switch actuated by each of said armatures, and energizing circuits for the electro-magnets so arranged that movement of the switch by one armature opens the energizing circuit of the electromagnet of the other armature and vice versa, substantially as described.

15. In a controlling device, a pair of electro-magnets having armatures mounted independently of each other, switch means actuated by each of said armatures, energizing circuits for the electro-magnets so arranged that movement of the switch means by one armature opens the energizing circuit of the electro-magnet of the other armature and vice versa, and means whereby each armature during a portion of its movement holds the other armature against movement, substantially as described.

16. In a controlling device, a pair of electro-magnets having armatures mounted independently of each other, switch means actuated by each of said armatures, energizing circuits for the electro-magnets so arranged that movement of the switch means by one armature opens the energizing circuit of the electro-magnet of the other armature and vice versa, means whereby each armature during a portion of its movement holds the other armature against movement, and spring means applied to said armatures to cause the same to move quickly when released, substantially as described.

This specification signed this 8th day of April, 1919.

SAM G. LANGLEY.
